UNITED STATES PATENT OFFICE.

JOSEPH M. DUNCAN, OF SILVER SPRINGS, NEW YORK.

SALT-GRAINING APPARATUS.

SPECIFICATION forming part of Letters Patent No. 349,931, dated September 28, 1886.

Application filed June 19, 1886. Serial No. 205,627. (No model.)

To all whom it may concern:

Be it known that I, JOSEPH M. DUNCAN, of Silver Springs, county of Wyoming, in the State of New York, a citizen of the United States, have invented certain new and useful Improvements in Salt-Graining Apparatus, of which the following is a specification, reference being had to the accompanying drawings, in which—

10 Figure 1 shows a side elevation of my mechanism with one side of grainer removed, said view being taken on line *x x*, Fig. 2; Fig. 2, an end elevation of elevator and carriage and section of grainer; Fig. 3, a horizontal section 15 on line *y y*, Figs. 1 and 2; Fig. 4, a horizontal section on line *z z*, Figs. 1 and 2. Fig. 5 is a front elevation of conveyer, taken on line *w w*, Fig. 1; and Fig. 6 represents an enlarged detail view of platform-leg and shifting mech- 20 anism.

Similar letters and figures of reference indicate corresponding parts throughout the several views.

The object of my invention is to improve 25 the construction and operation of apparatus and machinery for the removal to the bins of the salt (sugar, &c.) from the crystallizing apparatus, commonly called a "grainer," wherein in the salt is crystallized in a flat-bottomed 30 vat of wood heated by horizontally-disposed steam-pipes supported above the bottom of the vat in any ordinary way. It is constructed as follows:

A is the grainer, consisting of a water-tight 35 wooden vat of any desired depth, say one foot, supported upon the floor of the building, and provided with steam-pipes 1, suspended therein, with platforms or partial covers made in sections 2 3 4. These platforms are made 40 upon joists 5, and the ends of these joists project somewhat beyond the flooring upon them, resting upon cross-girts *a*, supported by legs *b*.

B B B are the upright posts of the building, and C C C are horizontal stringers mounted 45 upon these posts in any ordinary manner; and D D are other stringers set upon these posts as a trackway, and hereinafter designated as the "trackway D," and which extends either across or lengthwise of the building in a direction transverse to the grainer or 50 series of grainers. Upon this trackway I

mount the upper elevating-carriage frame consisting of posts 7 7 set uprightly upon the sills 8 8. These sills are made in sections supported upon the stringers C, with stationary pieces 9 of wood between the ends of the sill-pieces, and these sills 8 and pieces 9, when coincident, form another trackway, which, for convenience, I hereinafter designate as the "trackway 10," and this trackway extends 6c in a line lengthwise of the grainer. Upon this trackway I mount upon rollers my traveling elevator-carriage F, consisting of bed 11, which I mount upon the rollers 12 in any ordinary way, the rollers standing upon the 65 trackway 10, (sills 8.) Upon this bed I erect upright posts 12^a, upon which I journal the drum 13, upon which I wind the rope 14, and upon the inner faces of posts 7 I place the rack-bars 37. Upon other uprights I 70 journal the guide-wheels 15, and upon the bed 11, between its bars and in line with the wheels 15, I mount the large sheave 16. Between the side bars of the bed 11, I also mount in proper bearings the sprocket-wheels 75 17, both upon the shaft 26. From the bottom of this bed I suspend the elevator-legs 18 19 downward, one, 18, vertical, and the other at an angle or bracing, and between these legs—that is, between each pair of them—I mount a 80 shaft in proper bearings, upon which I mount another pair of sprocket-wheels, 20. I place a pair of elevator-legs upon each side of the bed 11, and upon the sprockets 17 and 20, I place a double chain-belt, between which 85 chains I carry my buckets 21. These chains also run over the guide-sprockets 22, located upon the legs 18 19, about as shown in Fig. 2. Upon the bed 11, I also mount tightener sprocket-wheels 23 in such manner that I can, 90 by removing them from the belt, leave it loose, so that I can readily uncouple it. The arrangement of the sprockets 20 and leg-pairs 18 19 gives the buckets a straight draw across the bottom of the grainer. Upon the elevator-legs, adjacent to their lower ends, I secure the horizontal rack-bars 24, the upper or rack face of which is somewhat beveled at each end. The legs *b* are mounted upon the joists 25, which also support the girts *a* upon the 95 axle-pin secured in the end of the joists, and upon which pin I removably mount the loose

pinion 27. In the body of this pinion I cut two or more curved slots, which receive the stop pins 28, secured in the leg b.

29 is a grooved idler-pulley mounted upon 5 a shaft and standing about midway between the pairs of the posts 7, and 30 is my grooved drive-wheel. Around the drive-wheel 30, idler 29, guide-wheels 15, and sheave 16 I 10 reeve an endless rope or cable, 31, extending in a direction lengthwise of the carriage F, as shown in Fig. 1, so that when power is applied to the drive-wheel 30 all of these several wheels revolve. As the sheave 16 revolves its shaft 15 operates the bevel-gears 32, revolving the sprockets 17, and by the screw-gear 33 the drum 18 is revolved, winding up the rope 14.

34 is another (double) screw-gear mounted upon the frame 35, which is suspended upon the door-hangers 36, standing upon the track-way E, which is suspended from above. From 20 this frame 35 ropes or chains hang down, and I can fasten their lower ends to the projecting ends of the joists 5; and 36^a is a hand-wheel, by which I operate the gears 34 to wind up or 25 unwind these chains to raise or lower a section of the platform, as 3, as well as the other sections when desired.

38, Fig. 4, are horizontal shafts upon the upper carriage, mounted so as to bring the pinions 39 into gear with the rack-bars 37 upon 30 the posts 7. Upon these shafts I mount screw-gears 40, to operate the sheave 41, around which I place the endless rope 42, and by operating this rope I revolve the pinions 39 and raise or 35 lower the trackway 10, and with it the carriage F and all its parts, including the elevator-legs, chain-buckets, drums, &c.

43 is a hinged chute into which the buckets empty, and which discharges the salt, &c., upon 40 that particular platform 2 over which the carriage F then stands.

D-D are the timbers set upon the posts B above and in a line transverse to the track-way E, and are heretofore designated by me 45 as "trackway D."

44 and 45 are the side and end bars of the upper carriage-frame, which is supported by the wheels 46, standing upon the trackway D, said wheels being mounted upon gudgeons projecting beyond the ends of the bars 45, and the pinion-shafts 38 are mounted in boxes set upon the bars in the brackets 47, which also operate as guides for the posts 7 as they are raised and lowered, as hereinafter described. The 50 idler 29 is mounted upon this upper carriage-frame, as is shown in Fig. 4 of the drawings. The trackway D is also made in sections, and 55 48 is a rope and pulleys for raising a section, when desired, which is sometimes necessary, 60 as it is on about the same level as and stands across trackway E.

I operate my device as follows: Taking as a starting-point the time when a grainer-vat is empty and when I desire to shift the elevator 65 to another grainer, I first connect the chains to the joists 5 of platform 2, as shown in Fig. 5 on platform 3, and by operating the hand-

wheel 36^a, I elevate that platform to about the height shown in Fig. 1 by the dotted lines s s above platform 3. I then, by the rope 48, 70 raise a section of trackway D up out of the way, and then run the so-elevated platform-section off to one side, it being carried by the hangers upon trackway E until the top of the grainer is uncovered at that point, and 75 lower the section of track-way D back into place again. I then, by operating the rope 42, rotate the sheave 41, screw-gears 40, shafts 38, and pinions 39, and these pinions 39, operating upon the rack 37, raise the 8c sills 8 and the whole of the carriage-frame, carrying with them the carriage F and the elevator, raising the legs 18 19 and the lower part of the chain-bucket belt out of the grainer until it stands above the top of the grainer. 85 (See dotted lines t t, Figs. 1 and 2.) I then run the whole carriage-frame so elevated over to the next grainer, the wheels 46 carrying it upon the trackway D until the elevator stands above the end of the grainer. At one end of 90 the grainer I shorten up the steam-pipes so as to leave a space (see Fig. 1) to receive the elevator-legs and belt and buckets, which are spread to about the width of the grainer. (See Fig. 2.) I then throw the screw 33 out 95 of gear, so that the drum 13 will not revolve. I then run the conveyer (applying this term to the aggregation consisting of the frame 35, hangers 36, gears 34, and chains) back and put the platform 2 into place again, remove 100 the chains, and switch the conveyer around behind the carriage F. These switches are in the trackway E, and are of any ordinary construction, and are not shown in the drawings. I then start up by applying power to the 105 drive-wheel 30, operating the wheel 31 as a belt, rotating the sheave 16, which transmits the power to and rotates the sprockets 17, and this sets the elevator-belt into motion. As soon as thus started, I lower the elevator-legs 110 gradually by reversing the operation of the pinions 39, engaging the rack 37 on posts 7. I lower in this way as fast as the buckets remove the salt until the lower ends of the legs 115 18 19 are close to the bottom of the grainer, at which time the buckets will run close enough to the bottom to clean it sufficiently of salt. When I have thus lowered down, I throw the screw 33 into gear so as to revolve the drum 13, and this revolution will wind up the rope 120 14, one end of which is secured to the building, as at 49, above the end of the grainer opposite to the starting-point of the elevator. This drum slowly winding up this rope draws the carriage F slowly along the trackway 10, 125 and this carriage carries with it in this movement longitudinal to the grainer the elevator, so that the buckets clean the salt out of the grainer as they thus move along sidewise in the grainer until they thus traverse the whole 130 length of the grainer. As the elevator thus traverses the grainer longitudinally it encounters the first pair of legs, b, which if rigid would stop further progress, as they stand in

the grainer; but just before the elevator reaches these legs the racks 24, one on each side, engage with the pinions 27, and their inclined faces raise the pinions, carrying with them 5 the joists 25 until the stop-pins 28 travel the length of the slots, when, with the continued movement of the elevator and consequent travel of the pinions 27 upon these racks, the legs being raised free from the bottom and the 10 pinions being stopped in their loose revolution commence to swing around, as shown by the dotted lines, Figs. 1 and 6, until when the pinions have traveled the entire length of the rack they disengage from the rack, and the 15 legs are left standing again vertical and upon the bottom of the grainer, supporting the joists 25 and platform-sections. As each succeeding pair of legs *b* is reached by the elevator this same operation is repeated. These platforms 20 extend longitudinally to the grainer, but are not as wide as the grainer, leaving the spaces shown in Fig. 2 on each side of the platform, which spaces are wide enough to give free passage to the elevator-legs 18 19, and I thus 25 remove the legs *b* to get them out of the way of the buckets. As the salt is taken up in the buckets it is elevated to the sprockets 17, and as the belt passes over these wheels the buckets in succession dump their load into the 30 chute 43, whence the salt falls upon the platforms. This chute is hinged or pivotally mounted, so that I can divert the flow of salt to any part of the platform I desire. The salt thus deposited upon the platforms is left 35 there to drain until thoroughly drained and comparatively dry, and the saturated brine-drippings fall directly into the grainer and no brine is lost, and this is very important, as the buckets elevate considerable brine 40 with the salt, and the salt is wet and quite slushy when it reaches the platform. Then when the elevator has reached the end of the grainer and thus removed the salt, I stop the elevator, reverse the screw-gear 33, and 45 start up again. The drawings only show one rope, 14, connected to the drum 13; but I usually use two ropes, so disposed that as one. 14, winds up on the drum the other is unwinding, each rope working at or adjacent to 50 each end of the drum. The reverse motion of the gear 33 turns the drum the other way, unwinding the rope 14 while it winds up the other one, and as the other winds onto the drum it draws the elevator and carriage F 55 back to the starting-point, and thus cleans up the grainer, if deemed necessary so to do. If not deemed necessary—that is, if it is sufficiently cleaned—I uncouple the elevator-belt, run the chain-belt and buckets out of the 60 grainer, remove the pinions 27, and lay them on the floor, and then as the elevator is run back it passes along free and unobstructed to the starting-point. I am then ready to remove the elevator, &c., over to another 65 grainer-vat. When the salt upon the platforms 3 4, &c., has sufficiently drained, I run

up the conveyer, hitch the chains upon the joists 5, and run the platform-section and salt off to the bins upon the trackway E, but first raising a section of the trackway D out of the 70 way. This trackway E extends out into the bin or cooling-room, and is there provided with switches, whereby I can run the platform and salt to any desired bin, and, furthermore, by means of which connection is so made 75 with the series of grainers as to readily admit of the transfer of the conveyer from grainer to grainer, and the salt then deposited in the bins is dry and ready for packing, &c., or substantially so; or the salt may be discharged 80 from the elevator-buckets, or spout 43, directly into a conveyer, of any ordinary construction, through which conveyer it can be conducted by any ordinary devices directly to the bins, and be deposited therein without 85 any intermediate draining.

The drawings show a form or style or styles of mechanism by which I can accomplish my work; but I do not limit myself hereby to any specific mechanism or form of mechanism, reserving to myself the right to use any equivalent or substitute mechanisms for the application or transmission of power for elevating, carrying, or lowering the several devices shown. 95

Having described my invention, what I claim as new, and desire to secure by Letters Patent, is—

1. In a salt-grainer, an elevator operating transversely to the grainer and simultaneously 100 traversing it longitudinally, substantially as described.
2. In a salt-grainer, a carriage, F, mounted upon the trackway 10 and carrying the elevator, substantially as shown and described. 105
3. A salt-grainer constructed with removable sectional platforms mounted upon legs standing in the grainer, substantially as shown and described.
4. In a salt-grainer, the slotted pinions 27, 110 mounted upon joists 25, in combination with the legs *b*, provided with stop-pins 28, constructed and operating substantially as set forth.
5. In a salt-grainer, the combination of the 115 slotted pinions 27, mounted upon joists 25, and legs *b*, provided with pins 28, with the rack 24, mounted upon the elevator-legs, constructed and operating together substantially as described, for the purposes set forth.
6. The combination of the drum 13 and rope 14 with the carriage F, mounted upon the trackway 10, constructed and operating together substantially as described.
7. In a salt-grainer, the conveyer consisting of frame 35, gears 34, wheel 36^a, and chains, and the hangers 36, mounted upon the trackway E, in combination with the platform sections, constructed and operating together substantially as shown and described. 125
8. In a salt-grainer, the combination of sills 8, posts 7, provided with rack 37, shafts 38, 130

provided with pinions 39, and with an actuating mechanism, with the carriage F, substantially as shown and described.

9. In a salt-grainer, the combination of the 5 posts 7, provided with rack-bars, pinions 39, and carriage F, in combination with the frame 44 45, rollers 46, and trackway D, constructed and operating together substantially as shown and described.

10. A salt-grainer provided with platforms standing above it upon legs automatically removed and replaced by the movement of the elevator, substantially as shown and described.

11. In a salt-grainer, an elevator consisting of legs 18 19, disposed in pairs rectangularly 15 and carrying the sprockets 20 22, chain-bucket belt 21, and sprockets 17, in combination with and supported by the carriage F, substantially as shown and described.

In witness whereof I have hereunto set 20 my hand this 8th day of June, 1886.

JOSEPH M. DUNCAN.

In presence of—

LEON DE BANCOURT,
W. A. MORGAN.
